ELECTRODE HOUSING FOR ELONGATED
TUBULAR LAMPS AND TERMINAL CON-
TACT THEREFOR

Samuel C. Miller, New York, N. Y.; Rosalie E. Miller, executrix of said Samuel C. Miller, deceased.

Application August 28, 1951, Serial No. 243,959

3 Claims. (Cl. 339—50)

1

This invention relates to a high voltage electrode housing and a terminal assembly therefor. The invention more specifically relates to an insulator housing and a terminal contact supported thereon whereby tubular illuminants, such as those employed for illumination by high voltages such as cold cathode discharge tubes, neon sign tubes, may be mounted upon a frame or plate.

Still more particularly, this invention relates to, and it is an object thereof to provide, an insulator housing to be attached to a sign or similar metal frame for mounting tubular sign illuminants for outdoor illumination or advertising display, and which will satisfy rigid requirements as to drainage of any accumulated moisture or rain, including the minimizing of entrapping detritus or insects, which would tend to cause break-down in insulation or shorting between the terminal contact and the frame of a high voltage illuminating assembly.

My invention, in a measure, involves an improvement of, and is a continuation-in-part of my invention described and illustrated in my application Serial No. 225,393, filed May 9, 1951, which, among other things, also involves an improvement over my Patent No. 2,046,960 of July 7, 1936.

My invention, in its more specific form, involves the provision of an insulator housing and contact support whereby the terminal ends of a high voltage tubular illuminant may be properly supported on a frame assembly in which maximum drainage is afforded by the employment of a contact which is supported by the housing, to increase the drainage when used, rather than to tend increasingly to form an obstruction. Furthermore, my invention resides in the provision of a housing employing a collar-like insulator which is cast with drainage walls and so mounts the terminal contact that, in use, drainage is augmented and obstruction is minimized in applying the terminal or electrode end of the tube into contacting relationship, thus enlarging the clearance space around the electrode end of the tube, when put into use, and facilitating the clearance of insects or like detritus which accumulate, and facilitating the inspection of such condition by a construction which permits the use of transparent material, such as glass, without sacrificing the requisite practical strength and size for the purposes intended.

Still further, it is an object of this invention to provide a housing which effects substantial economies by reason of its contour lending itself to economical and commercially practical glass

5 molding operations, especially involving glass which has high thermal resistance, thus providing effective insulating protection, low cost maintenance and simplicity of molding, to produce a relatively low cost, economical insulator.

Still more particularly, it is an object of my invention to provide a housing for an illuminant of the character described which supports a terminal contact wherein the housing serves as an effective mechanical and electrical shield, axially positions the illuminant and, in use, tends to enlarge clearance between the insulator and the terminal end, whereby economies in production as well as efficiency in operation are assured.

To attain these objects and such further objects as may appear herein or be hereinafter pointed out, I make reference to the accompanying drawing forming a part hereof, in which—

Figure 1 is a longitudinal plan view showing 20 an insulator assembly in accordance with my invention, with a part of the support in section;

Figure 2 is a section on the line 2—2 of Figure 1;

Figure 3 is an end view in the direction of the lines 3—3 of Figure 2, before application of the tube in position;

Figure 4 is a perspective view of the terminal contact spring.

Making reference to the drawing, there is provided a housing 10 of generally cylindrical contour, having molded or otherwise formed on its peripheral surface screw threads 11. To one side of such threaded portion is formed a flange 12, cooperating with a screw threaded collar 13 to clamp the insulator to a frame 14, when projected through the aperture 15. Adjacent the end 16 of the insulator there may be formed an additional flange 17, which cooperates with the flange 12 to provide a circuitous electrical path, increasing the insulating value, as will be readily understood.

The insulator has an axial boring 18, whose mouth 19 adjacent the end 16 flares rearwardly to indent the boring to the end 20. Adjacent to the end 20 the insulator at its periphery is formed with an annular groove 21, defining a flange 22 about substantially the entire end. Communicating with the annular slot, leading out to the end 20 there is formed a longitudinal slot 23 comprising a seat formed by the abutments 24 and 25. To one side of the stud-like extension 26 there is formed an angularly directed slot 27 also forming a passage from the groove 21 to the end 20.

With this construction there is provided a con-

tact spring 28 which normally comprises convolutions formed in a spiral, the central convolutions 29 whereof are relatively closely wound and preferably progressing in pitch to merge into peripheral convolutions 30, two or three being convoluted cylindrically. The said cylindrical convolutions are thereby joined to the spiral portion by the single angular arm 31. The number or density of the convolutions will depend upon circumstances as will become apparent as this description proceeds.

The convolutions 30 serve likewise to support a conductor terminal clip 32 which is positioned to project its shank 33 in the seat 23 between the abutments 24 and 25. A looped tongue 34 spans and is crimped about one or more of the convolutions 30, within the groove 21. The conductor terminal 32 illustrated will be recognized as the usual Fahnstock coupler having engaging fingers 35, and it will be understood that other coupling means may be employed.

With a construction as described, the spiral contact spring 28 is assembled with the insulator 18 by threadedly engaging the convolutions 30 through the flange 22 and entering the same by directing the end of the wire into the angular slot 27. The convolutions 30, being tightly wound within the groove 21, will have the arm 31 offset to conform end 20 extending through the angular slot 27 and project the spirally positioned convolutions across and flush with the end 29 of the insulator. With this assembly, the illuminant tube 36 may be axially projected through the opening 19, to have the electrode terminal cap 37 thereof engage with the spiral contact 28 and push it outwardly and expand the spirals helically as well as spirally.

The relative proportions of the tube 36 to the insulator 18 are such as to project the terminal cap 37 against the contacting spring 28, distending the convolutions as well as to cause the axial convolution 29 to conform to the cap 37. Thus, an axial support is provided, as well as a contact for the terminal cap of the tube. The intermediate convolutions between the arm 31 and the axial portion 29 are drawn angularly away from the end 20, leaving a free passageway between the tube 36 and the walls defining the boring 18 of the insulator. The relationship of the diameter D to the length L may conform to the underwriter's requirements for inaccessibility of the coil 28 with relation to the mouth 19.

A short length L provides the requisite mechanical shielding while permitting a larger or steeper flare from the mouth 19 to the end 20.

The construction of the insulator makes possible the molding and casting of the same with difficultly castable materials, thus permitting the use of simple, multi-part molds for high fusion, thermally resistant, thermal glass having a high dielectric strength and a low coefficient of thermal expansion characteristic of the boro-silicate glass manufactured under the trade-mark "Pyrex."

The insulator accordingly may be made by the manufacturing procedure outlined in my Patent No. 2,046,960, with the additional features indicated in my applications Serial No. 77,015, now Patent No. 2,630,469, March 3, 1953, and Serial No. 104,556 with regard to the flare of the interior boring providing rapid drainage away from the mouth of the housing. The shortened length of housing so that the spiral contacting spring is distended when in contact with the terminal of the illuminant serves to provide a sharp drainage

angle interiorly of the boring, without sacrificing strength. Furthermore, the spiral contact is attenuated with regard to the opening adjacent the end 20, rather than to increase the obstruction, as is the case with a spring contact previously used by me which, when compressed within the housing, expands in diameter.

It will thus be observed that by the construction provided increased efficiency for drainage is secured, without sacrificing mechanical shielding or electrical insulation. Furthermore, the more extensive the engagement of the terminal cap 37 with the spiral contact 28, the greater will be the clearance between the insulator walls and the axially positioned cap.

In general, it will be observed that I have provided an insulator assembly for tubular illuminants which may be assembled especially on a vertical frame in which long life is assured by reason of ready drainage of rain water, and clearance of insects and detritus, and in which a wide variety of insulator materials, particularly glass, multiform glass, and ceramics or porcelain, may be employed, thereby effecting economies with respect of the material and the labor and apparatus for their production and assembly.

Having thus described my invention and illustrated its use, what I claim as new and desire to secure by Letters Patent is:

1. In a high voltage electrode housing for supporting an electrode tube on a frame, having a substantially cylindrically contoured exterior body portion having an opening extending from end to end, a mouth at one end thereof through which the electrode tube may pass, a rim at the other end thereof, an integral flange on said exterior portion between said ends adjacent said mouth, means on said exterior portion for mounting the housing to the frame, the opening on the interior of said housing being outlined by walls continuously and gradually flaring toward the rim end forming a drainage passage extending to the rim end, said rim end having indentations exteriorly positioned comprising seat portions arranged for supporting terminal contact means against displacement transversely of said housing adjacent said rim end, the combination therewith of a terminal contact comprising a convoluted conductor having a portion mounted across the rim end and a portion including an anchoring convolution engaging said seat portions and terminal conductor clip means on said housing supported by said anchoring convolution, the terminal contact upon positioning of the electrode tube, leaving a substantially clear passage for drainage.

2. In a high voltage electrode housing in accordance with claim 1 wherein the terminal contact comprises a spiral and the anchoring convolution comprises a helix.

3. In a high voltage electrode housing in accordance with claim 1 wherein the terminal contact comprises a spiral wire spring having a peripheral radial arm merging into peripheral convolutions of helical outline.

SAMUEL C. MILLER.
